UNITED STATES PATENT OFFICE.

GEORGE R. KUNKLE, OF ELYRIA, OHIO, ASSIGNOR TO THE GENERAL PHONOGRAPH MANUFACTURING COMPANY, OF ELYRIA, OHIO, A CORPORATION OF OHIO.

DESIGN FOR A PHONOGRAPH-CASING.

58,150.

Specification for Design. Patented June 14, 1921.

Application filed December 1, 1919. Serial No. 341,815. Term of patent 7 years.

To all whom it may concern:

Be it known that I, GEORGE R. KUNKLE, a citizen of the United States, residing at Elyria, in the county of Lorain and State of Ohio, have invented a new, original, and ornamental Design for Phonograph-Casings, of which following is a specification, reference being had to the accompanying drawing, forming part thereof.

Figure 1 is a plan view of a phonograph casing, showing my new design, and Fig. 2 is an elevation thereof.

I claim:

The ornamental design for a phonograph casing, as shown.

GEO. R. KUNKLE.
